UNITED STATES PATENT OFFICE.

JOHN COATES, OF WORCESTER, ENGLAND.

SUPERHEATER.

1,070,115.

Specification of Letters Patent. Patented Aug. 12, 1913.

Application filed May 3, 1913. Serial No. 765,344.

To all whom it may concern:

Be it known that I, JOHN COATES, a British subject, residing at Worcester, county of Worcester, England, have invented certain new and useful Improvements in Superheaters, of which the following is a specification.

This invention relates to improvements in superheaters, more particularly for use with locomotive and marine boilers or with other boilers of a similar type.

The invention consists essentially in introducing a superheater tube into some or all of the fire tubes each superheater tube being closed at one end and having cast iron rings shrunk thereon, and containing a second tube concentric therewith. The cast iron rings are preferably provided with gills or ribs arranged either spirally or longitudinally to direct the flow of the gases.

The invention will be fully described with reference to the accompanying drawings forming part of the specification.

Figures 1 and 1^a together constitute a longitudinal vertical section through a locomotive boiler showing the invention applied thereto. Fig. 2. is an end view of the same. Fig. 3. is an outside elevation of one of the superheater tubes. Fig. 4. is an enlarged section of a superheater tube. Fig. 5. is a section on line x—x Fig. 4. Fig. 6. is an enlarged section showing the connection of the superheater tube to the header.

A superheater tube is inserted in some or all of the fire tubes B which may be enlarged to receive them. The superheater tube is composed of two concentric tubes A, A', the inner tube A' being maintained in position by the supports a, (Fig. 6). The outer tube A is closed at one end and opens at the other end into the chamber C' of the header C connected with the saturated steam space D at the top of the boiler. The inner tube A' is open at both ends, the inner end opening into the outer tube A and the outer end into the chamber C² of header C leading to the cylinder pipe E.

A separate header is preferably provided

for each vertical row of superheater tubes A connected to a common chamber or pipe a leading to the steam space D above the boiler and to a pipe E leading to the cylinder.

Each vertical header C may also be provided with an additional chamber F containing live steam. Holes f, (Fig. 6), are bored in the wall f' of the chamber F around the part where the tube A is fixed so that steam jets will blow through the holes f into the fire tubes B around the superheater tube A in order to keep the latter clean and free from soot.

Rings H of cast iron, steel or other material are shrunk onto the outer surface of the tubes A to protect them. These rings H are arranged side by side so that a complete covering of the tube A is obtained. The rings H act as equalizers for the heat, since if there be an excess of heat in the gas flowing through the fire tubes, it will be absorbed by these rings and will be given out to the steam in the superheater tubes when the heat in the fire tubes is somewhat diminished. In this way the rings H act as equalizers, so that a fairly constant supply of heat is given to the superheater. The cast iron rings H are preferably provided with ribs or gills h arranged either longitudinally or spirally as shown in Figs. 3, 4 and 5 in which case each ring is so fitted that the gills thereof align with the gills of the preceding ring forming a series of spiral passages around the tube A.

The tube A is supported in the tube B by the supports b, (Fig. 1^a), or the gills h may be of such a depth that their outer edges engage on the inside of the fire tubes B and maintain the superheater tube A centrally in the fire tube.

The closed ends of the tubes A may be only covered with plain rings without gills.

The ends of the tubes A are covered with a cast iron cap or end piece h' with or without ribs or gills as desired.

What I claim as my invention and desire to protect by Letters Patent is:—

In a fire tube boiler the combination with

a fire tube of a superheater tube placed therein, metallic rings on the outer surface of the superheater tube and alining ribs on the metallic rings to form continuous passageways for the gases extending longitudinally of said tubes.

In testimony whereof I have hereunto set

my hand in presence of two subscribing witnesses.

JOHN COATES.

Witnesses:

ALFRED S. CLEMENTS,
H. A. AUDREY.
